UNITED STATES PATENT OFFICE

ALBERT TONE, OF MESA, ARIZONA

FOLDING TABLE AND CABINET FOR AUTOMOBILES

Application filed June 7, 1926. Serial No. 114,121.

This invention relates to a container or casing adapted to be extended to form a table and to have containers disposed therein adapted to carry utensils, and particularly to such a device constructed and arranged to be carried on the running board of an automobile.

It is quite a common custom for automobileists to picnic or take their meals along the route and it is desirable on such occasions to have a table, and it is also desirable and convenient to have a table which can be collapsed into small space and conveniently carried. It is also desirable to carry along the necessary utensils for use in preparing and serving a meal.

It is an object of this invention, therefore, to provide a box or casing adapted to be carried on the running board of an automobile and collapsed in compact form, which box or casing comprises means arranged to be extended to form a table.

It is a further object of the invention to provide such a device as is above set forth, which is arranged to carry several containers in which the necessary utensils can be stored while enroute.

It is a further object of the invention to provide a box or container adapted to be carried on the running board and collapsed in compact shape and adapted to be extended to form a table when desired, the same being provided with detachable legs, and said casing having means by which it is secured to the running board adapted to co-operate with the containers carried therein when the device is assembled in extended position.

These and other objects and advantages of the invention will be fully set forth in the following description made in connection with the accompanying drawings, in which like reference characters refer to similar parts throughout the several views and in which:—

Fig. 1 is a view in front elevation of the device in collapsed form showing the same on a running board, some portions being broken away and others shown in vertical section;

Fig. 2 is a horizontal section taken on line

2—2 of Fig. 1 as indicated by the arrows, the device also being shown in extended position in dotted lines, as indicated by the arrows;

Fig. 3 is a vertical section taken on line 3—3 of Fig. 1, as indicated by the arrows, showing some parts extended;

Fig. 4 is a partial view in end elevation of the device with the supporting legs in position, certain parts being broken away;

Fig. 5 is a vertical section taken on line 5—5 of Fig. 2, as indicated by the arrows;

Fig. 6 is a view similar to Fig. 4, showing a modified structure;

Fig. 7 is a view in front elevation of a modified form of the device, showing the same in extended position;

Fig. 8 is a view in side elevation of the device shown in Fig. 7;

Fig. 9 is a top plan view of the device shown in Fig. 7;

Fig. 10 is a plan view of some of the parts used with the device shown in Figs. 7, 8 and 9; and

Fig. 11 is a view of a top portion of the legs used with said device.

Fig. 12 is a view similar to Fig. 1, showing a modification.

Referring to the drawings, particularly Figs. 1 to 5, a device is shown comprising a casing or box 15 having the top 15^a and the ends 15^b. Said casing is open at either side and has the bottom 15^c and is adapted to rest on a suitable support such as a running board 16 of an automobile. Said casing or box 15 may be suitably reinforced at the corners. Said box has brackets 17 secured to the end portions 15^b which brackets are of U-shape in side elevation and thus have top and bottom projecting arms, the lower of which is flush with the bottom of the casing and adapted to rest on the running board 16. Said arms are perforated to receive the bolt 18 having the wing heads 19 and extending through said apertures and the running board. Said threaded end is adapted to engage in a threaded hole in a strip 16^a secured to the underside of the running board. The casing 15 has a board or panel 20 extending between the end portions 15^b adjacent its lower end

100

and cross pieces 21 extending transversely of the end portions 15^b at the inside thereof adjacent the top of the member 20. A board or panel 22 is hinged at its outer lower edge 5 to the upper inner edge of member 20 which board or panel is of a length slightly less than the distance between the inside edges of the ends 15^b. The board or panel 22 has hinged at each end thereof the end boards 23, 10 each of which is slightly less than half the length of said board or panel 22, said end boards 23 also being somewhat smaller in width than the board 22. Buttons 23^a and 23^b are provided for holding the panels 22 and 15 23 in folded position, the button 23^a being secured to the edge of the top 15^a and the button 23^b being carried at one end of one of the panels 23. The space below the cross pieces 21 has therein triangular shaped pieces 24 and a central triangular shaped piece 25 forming therebetween inclined channels converging toward their upper ends, the inner sides of said channels meeting substantially at the bottom of the cross pieces 21. The 20 member 25 has recesses 25^a at each of its sides adapted to receive plate springs 26 bent as shown in Fig. 4, to have angular portions extending into the channels formed by members 24 and 25. Legs 27 rectangular in cross 30 section are provided, adapted to fit in said channels and said legs have V-shaped notches 27^a at their inner sides into which the springs 26 are adapted to extend when the legs are in proper position to hold said legs in place. 35 A pair of containers 29 and 30 respectively are provided, the latter of which is disposed in the lower portion of the casing 15 between the ends 15^b and the said panels 20, and the former of which is supported on top 40 of the casing 30 and between the end portions 15^b and the said boards or panels 22. The containers 29 and 30 which are rectangular in form, both have a central bracket 29^a formed of a flat strip bent into rectangular shape secured therein at their central portion, said casings being open at their top sides. The casings 29 and 30 are of a height to fit snugly between the upper and lower arms of brackets 17 and said casings and arms 29^a have apertures 29^b extending vertically therethrough of a size to receive the bolts 18. 45

In operation when the device is in collapsed position on the running board of an automobile, it will appear as shown in Fig. 1. The 55 panels 22 and 23 are folded into the sides of the box 15 as shown in Fig. 4 and held in place by the buttons 23^a and 23^b. The container 30 is disposed in the bottom of the casing 15 and the container 29 is disposed in the 60 upper portion thereof. When it is desired to set up the device to form a table, the bolts 18 are removed and the casing 15 lifted from the running board. The panels or side boards 22 are folded outwardly as shown in dotted 65 lines in Fig. 2 and the end boards 23 then

folded outwardly at the ends of the boards 22. The containers 29 and 30 can now be placed in the brackets 17 as shown in Fig. 5 and will be disposed beneath the boards 23, extending across the ends of the box 15. As stated, the casings 29 and 30 fit in the brackets 17 and the holes 29^b align with the holes in said brackets so that the bolts 18 can be disposed through the holes in the brackets and holes 29^b. The containers 29 and 30 are thus firmly held in position and support the end boards 23. The legs 27 can now be placed in position by merely pushing the same upward in the channels in the end of the casing 15. The springs 26 will spring into the slots 27^a and the legs will thus be firmly held in proper position. The device now forms a very convenient table and the tops of the containers 29 and 30 are also accessible, if it is desired to have anything therein for use. The end boards 23 may 70 extend downwardly and engage panels 20 with one side edge, thus supporting boards 22 75 in horizontal position.

In the construction shown in Fig. 6, the device is constructed as heretofore described, 80 except that the side portions or panel 22 is hinged by the hinge 22^a at the outer front edge of the board or panel 20 instead of at the inner edge thereof. The end boards 23 are hinged to the board 22 as before, but 85 these boards will not now swing into the casing flush with the outer side of the panel 20 as shown in Fig. 4 but will project somewhat at the sides of the casing. The operation of the device is otherwise as described. 90

In the device shown in Figs. 7 to 11, a box or casing 35 is shown having end portions 35^a and a top 35^b projecting beyond the sides of said end portions. The casing has a bottom portion 35^c which is adapted to 105 rest on a supporting surface such as a running board as illustrated in Fig. 1. The end portions 35^a have angle brackets 36 secured on their outer sides and projecting outwardly therefrom, having horizontal flanges apertured to receive the upper ends of the bolts 37. The bolts 37 when the device is carried on the running board, would pass through openings in the running board in the same manner as illustrated in Fig. 1 and the lower 110 threaded ends of the bolts pass through the plates 16^a thereon. Said panels or boards 39 are hinged at their inner and upper edges to the outer and upper edges of the bottom board 35^c. The said boards 39 each have the end boards 40 hinged at their end portions and adapted to fold upwardly onto the board 39, the length of the boards 40 being slightly less than half the length of the board 39. The brackets 36 have a plate portion forming 120 a downwardly flaring recess therein open at its lower end and a pair of legs 41 are provided having beveled ends adapted to fit together to form a point as shown in Fig. 11, said legs being hinged at the inner sides of 125 130

said beveled ends by the hinge 42. The recess in the brackets 36 is adapted to receive the upper pointed end of the hinged pair of legs as shown in Figs. 7 and 8. A pair of boards 43 are provided of rectangular shape in plan and cross section, having spaced rectangular slots 43^a extending into their sides, said ends being so spaced that they will fit over the legs 41 immediately below the boards 40 and 35^c as shown in Figs. 7 and 8. The boards 43 have at their ends plates 44 secured thereto and projecting at one side thereof, said plates being apertured and threaded to receive the bolts 37 at certain times which will be hereinafter set forth. Each board 43 also has a threaded hole 43^b in a nut extending therethrough at the longitudinal center thereof and adjacent one edge.

In operation, when the device is to be carried in compact shape on the running board, the boards 40 will be folded over onto the top of boards 39 and both sets of boards will then be swung upwardly to the sides of the casing 35 and beneath the sides of the top portion 35^b. The legs 41 will be removed and these are made of a length so that they can be placed inside of the casing 35. The boards 43 are placed together as shown in Fig. 10 and disposed on the running board immediately under the bottom portion 35^c, the bolts 37 passing through the apertures in the overlapping lugs 44. The device is thus carried on the running board in very compact shape. If desired, one or more containers can also be carried in the casing 35 which containers will be similar to the containers 30 and 29 shown in Figs. 1 to 5.

When the device is to be set up in extended position, the same will be removed from the running board, the boards 39 and 40 will be folded outwardly as shown in Fig. 9, the legs 41 will be disposed in the brackets 36 as shown in Fig. 8 and the boards 43 will then be placed in position as indicated in Figs. 7 to 9. These boards will come directly beneath the boards 40 and the bottom 35^c and the bolts 37 in brackets 36 will align with the holes 43^b. The bolts will be passed through the boards 43 and into the brackets 36 and tightened in position by the heads 38 as shown in Figs. 7 to 9. The legs 41 will thus be held firmly in position and the device will be extended to form a convenient table as shown in Figs. 7 to 9.

In the modification shown in Fig. 12, the casing 45 is used, which is the same in all respects as the casing 15 shown in Fig. 1, except that it is somewhat higher relative to its width. The same has the brackets 17 secured at each end adapted to receive the bolts 18 as described in connection with Fig. 1, which bolts pass through the running board 16 and engage the strips 16^c therebeneath.

Said casing has the panel 46 thereon corresponding to the panel 20 and has the side por-

tion 47 hinged to the panel 46 in the same manner as the panel 22 is hinged to the panel 20. The sideboard 47 has hinged thereto the extension or end boards 48. The boards 47 and 48 fold up at the side of casing 45 and are held by the fastening means shown as the buttons 49 which are similar to the buttons 23^a and 23^b shown in Fig. 1. Instead of having the container in the lower part of the casing 45, two containers 50 are shown in the upper part thereof, the lower container 50 resting on the cross pieces 51 corresponding to the cross pieces 21 already described and the upper container 50 resting on the lower container 50. The containers 50 will have brackets or frames therein similar to the frames 29^a and said containers 50 are of a height to fit within the brackets 17 and will be held therein when the table is extended in the same manner as are the containers 30 and 29, as shown in Figs. 2 and 5. The containers 50 will thus support the end boards or extensions 48 when the device is in extended position, in the same manner that the containers 29 and 30 support the boards 23. The containers 50 will preferably be of the same width. Except for the feature of the casing 45 being higher and having the two similar containers 50 carried in the upper portion thereof, the form shown in Fig. 12 is similar in all respects to that shown in Figs. 1 to 5.

From the above description it is seen that applicant has provided a very simple and efficient casing or cabinet arranged to be folded into compact form and carried on a supporting surface such as a running board of an automobile and it can be quickly and easily extended to form a convenient table. The device is easily and simply made from few and simple parts. The same forms a very convenient device and one having a high degree of utility, and constitutes a decided advance in the art.

It will, of course, be understood that various changes may be made in the form, details, arrangement and proportions of the parts, without departing from the scope of applicant's invention, which generally stated, consists in a device capable of carrying out the objects above set forth, in the novel parts and combinations of parts disclosed and defined in the appended claims.

What is claimed is:

1. A device of the class described having in combination, a casing having fixed top and end portions and being open at its sides, adapted to be supported upon the running board of an automobile, said casing having side boards hinged thereto at each side about horizontal axes, a pair of end boards hinged to the end of each of said side boards, said boards being adapted to fold into said casing and to be extended at the sides thereof, removable containers receivable in said casing between said parts when in folded position

- within said casing and means for supporting said containers at the ends of said casing to form supports to hold said end boards in extended horizontal position.
2. A device of the class described having in combination, a casing having open side portions and adapted to be supported upon the running board of an automobile, boards hinged at each side of said casing, extension members hinged to said boards, said extension members and boards being adapted to fold up at the sides of said casing, brackets secured to said casing, means extending through said brackets adapted to secure the same to said running board and members adapted to extend beneath said extension members at the ends of said casing and to be secured by said means passing through said brackets for holding the boards and extension members in extended position.
3. A device of the class described having in combination, a casing having open sides and adapted to be supported upon the running board of an automobile, boards hinged at the sides of said casing along an axis extending longitudinally thereof, end boards hinged at each end of said boards, said side and end boards being adapted to fold up at the sides of said casing, U-shaped brackets projecting at the ends of said casing, bolts passing through said brackets for securing said casing to said running board, containers receivable in said casing, said containers fitting in said brackets and having apertures therethrough for receiving said bolts whereby said containers can be disposed beneath said end boards when extended for supporting the same and legs removably secured at each end of said casing.
4. A device of the class described, having in combination, a casing having fixed top and end portions and being open at its sides, side boards hinged at the sides of said casing and having extension members hinged thereto, said boards and members being adapted to be folded upward at the sides of said casing, and to be extended in a common horizontal plane, and a pair of superposed box-like containers receivable in said casing between said boards and extension members when the latter are in folded position within said casing, said containers being adapted to be positioned to support said boards and extension members in extended position.
5. A device of the class described having in combination, a casing having top, bottom and end portions and being open at its sides and adapted to be supported upon said bottom upon the running board of an automobile, side boards hinged at the side of said casing and having extension members hinged thereto, said boards and members being adapted to be folded upward at the sides of said casing, means for securing said casing to said running board when in folded

condition, members adapted to hold said side boards and extended members in extended position, said members being held in position by said means and supporting legs for said device when in such extended position.

In testimony whereof I affix my signature.

ALBERT TONE.
